UNITED STATES PATENT OFFICE.

HARRY L. WING, OF RUMFORD, MAINE, ASSIGNOR TO WING MACHINE COMPANY, OF RUMFORD, MAINE, A CORPORATION OF MAINE.

MUSIC-LEAF TURNER.

1,146,379.

Specification of Letters Patent. Patented July 13, 1915.

Application filed January 10, 1914. Serial No. 811,476.

To all whom it may concern:

Be it known that I, HARRY L. WING, a citizen of the United States, residing at Rumford, in the county of Oxford and State 5 of Maine, have invented new and useful Improvements in Music-Leaf Turners, of which the following is a specification.

The invention relates to music leaf turners, and more particularly to the class of 10 automatic music leaf turners.

The primary object of the invention is the provision of a music leaf turner wherein the music sheet turning arms are successively actuated for the turning of the sheets of 15 music in their order, the mechanism for controlling the arms being under the direct control of the operator or player of the piano or other instrument so that the music sheets will be turned at the required intervals without necessitating the manual manipulation 20 of the music.

Another object of the invention is the provision of a music leaf turner wherein the mechanism for turning the arms is actuated through the medium of a spring motor 25 which can be readily wound by the operator or player of the piano or other instrument.

A further object of the invention is the provision of a music leaf turner wherein after the leaves of sheet music have been turned in their successive order the same will be reversely moved for again bringing the pages or sheets of music to normal position, the reversing mechanism being under 30 the direct control of the player or operator of the piano or other instrument.

A further object of the invention is the provision of a music leaf turner wherein the music turning arms are actuated from frictional gearing which is driven from a main spring which is readily wound, the gearing being reversely driven through a reversing mechanism so that the leaves of the sheet music can be turned in either direction, that 40 is to say from right to left, and vice versa.

A still further object of the invention is the provision of a music leaf turner which is simple in construction, automatic in its action, thoroughly reliable and efficient in its 45 operation, and inexpensive in manufacture.

With these and other objects in view, the invention consists in the construction, combination and arrangement of parts as will be hereinafter fully described, illustrated in

the accompanying drawings, and pointed out in the claims hereunto appended.

In the drawings, Figure 1 is a front elevation of a music leaf turner constructed in accordance with the invention. Fig. 2 is a top plan view thereof, with the cover or 60 top removed. Fig. 3 is a vertical longitudinal sectional view thereof. Fig. 4 is a sectional view on the line 4—4 of Fig. 1, looking in the direction of the arrow. Fig. 5 is a sectional view on the line 5—5 of Fig. 1. 65 Fig. 6 is a sectional view on the line 6—6 of Fig. 1.

Similar reference characters indicate corresponding parts throughout the several views in the drawings.

Referring to the drawings in detail, the music leaf turner comprises a substantially oval-shaped casing A, which is adapted to be detachably fastened to the music rack of a piano or other musical instrument, and has 75 fixed interiorly thereof on one side wall a bearing 10 in which is journaled a driving shaft 11, one end of which projects exteriorly of the casing and has fixed thereto a coiled spring 12 which is held within a housing forming a knob 13 to which the other end of the spring is connected, and this housing carries on its inner face a ratchet 14 with the teeth of which engages a holding dog 15 which is secured to the casing, it being noted that on turning the housing 13 in one direction the spring 12 can be readily wound therein for the driving of the shaft 11 which carries at its inner end a beveled pinion 16 meshing with the beveled gears 17 80 and 18 respectively, which are loosely supported upon a driven shaft 19 which is journaled at right angles to the shaft 11 in bearings 20 suitably supported on the casing A of the music leaf turner.

Slidably splined to the shaft 19 between the gears 17 and 18 is a reversing clutch sleeve 21, the outer clutch ends 22 of which are adapted for engagement with the companion clutch faces 23 on the hub of the 100 gears 17 and 18 respectively, the sleeve 21 being engaged with a throw lever 24 which is pivoted at 25 in a bracket 26 secured interiorly of the casing A, the lever being of a length to extend exteriorly thereof so that it 105 may be manually manipulated for shifting the sleeve into locked engagement with either of the gears 17 and 18. It will be

noted that when the sleeve 21 is engaged with one gear 17 the shaft 19 will be rotated in one direction, while on shifting the sleeve 21 into engagement with the gear 18 the shaft will be rotated in the reverse direction. The bracket 26 is formed with an extension 27 to which is connected one end of a coiled retractile spring 28, the opposite end of which is connected with the throw lever 24 so that the sleeve 21 under the action of the spring 28 is normally sustained in engagement with the gear 18 so that the shaft 19 will be rotated in a direction to turn the music leaf arms from right to left for the proper turning of the music sheets.

Secured to the shaft 19 are driven wheels or disks 29, each being provided with a resilient tread piece or strip 30 at its periphery, these treads or strips 30 being disposed in slightly advanced relation to each other on the wheels or disks 29, and only extend about one-quarter of the peripheries thereof for frictional engagement with wheels or rollers 31 which are respectively fixed to the upper ends of shafts 32, 33, 34 and 35 arranged in interfitting relation to each other and supported in a bearing 36 within the casing A, the lower ends of these shafts being fitted with music leaf turning arms 37 which carry suitable clips for engagement with the upper edges of the music sheets or leaves. The bearing is adjustable within the casing A by means of the set screws 38 which are engaged in the base thereof and pass through slots 39 formed in the bottom of the casing A so that any wear on the rollers 31 or the tread pieces or strips 30 can be taken up by adjusting the bearing relative to the disks or wheels 29. The disposition of the tread pieces or strips 30 permits the turning of the arms 37 in successive order for the turning of the music sheets one after the other at the required intervals of time.

The wheel or disk contiguous to the bottom of the casing A is formed on the under face at diametrically opposite points with opposed pairs of stop lugs 40 with any one of which engages a locking lever 41 pivoted at 42 to a bearing 43 fixed within the casing A, the lever 41 being projected through the said casing and has loosely connected thereto a lifting rod 44 which extends in convenient reach of the operator or player of the piano or other musical instrument so that it can be lifted for releasing the lever 41 to free the shaft 19 so that it will rotate under the action of the spring 12 for the turning of the music leaf arm, the lever 41 being connected with a coiled retractile spring 45 which is also connected to a stationary bracket 46 fixed to the casing A, and this spring serves to normally hold the lever 41 in the path of the stop lugs 40 to engage in one of the same and thus nor-

mally hold the shaft 19 against rotation. After the music leaf turning arms 37 have been swung in one direction it is necessary to reverse the clutch sleeve 21 by shifting the lever 24, thus the spring 12 through the medium of the gear connections of the shafts 19 will rotate it in the reverse direction when the rod 44 is lifted to free the same, thereby turning the music leaf turning arms in the reverse direction, the lever 24 being held by the hand of the operator in such position until all of the leaves have been turned. To shift the clutch sleeve so that the leaves will be turned in the reverse direction it is necessary for the operator to depress the lever 24 and hold it in its lowered position against the resistance of the spring 28, thus the clutch sleeve 21 will mesh with the companion clutch 23, thereby reversing the action of the music leaf turner.

From the foregoing it is thought that the construction and manner of operation of the invention will be clearly understood, and therefore a more extended explanation has been omitted.

What is claimed is:

1. A music leaf turner comprising a casing, bearings formed within and without the casing in alinement with each other, a shaft journaled in said bearings, gears arranged in spaced relation to each other and rotatably loose on said shaft, a double clutch slidably keyed to the shaft between the said gears and alternately engageable therewith for the locking of each on the shaft, a second shaft journaled in the casing at right angles to the first-named shaft, a knob rotatably supported upon the second-named shaft without the casing and forming a spring housing, a coiled spring within said knob and having one end connected thereto and to the shaft, a ratchet formed on the knob, a trip pawl carried by the casing and engageable with the ratchet to lock the knob fixed on the winding of the spring, friction gears carried by the first-named shaft, music leaf turning members arranged in nested relation to each other, rollers mounted on the respective members and operated at intervals by the friction gears, means engageable with one of the friction gears for locking all of the same passive, and means for shifting the double clutch.

2. A music leaf turner comprising a casing, bearings formed within and without the casing in alinement with each other, a shaft journaled in said bearings, gears arranged in spaced relation to each other and rotatably loose on said shaft, a double clutch slidably keyed to the shaft between said gears and alternately engageable therewith for the locking of each on the shaft, a second shaft journaled in the casing at right angles to the first-named shaft, a housing rotatably supported upon the second-named

shaft without the casing and forming a spring housing, a coiled spring within said housing and having one end connected thereto and to the shaft, a ratchet formed on the 5 knob, a trip pawl carried by the casing and engageable with the ratchet to lock the housing fixed on the winding of the spring, friction gears carried by the first-named shaft, music leaf turning members arranged in 10 nested relation to each other, rollers mounted on the respective members and operated at intervals by the friction gears, means en-

gageable with one of the friction gears for locking all of the same passive, means for shifting the double clutch, and means acting 15 on the last-named means to hold the double clutch normally engaged with one of the friction gears.

In testimony whereof I affix my signature in presence of two witnesses.

HARRY L. WING.
